UNITED STATES PATENT OFFICE.

WILLIAM J. M. WEAVER, OF PHILADELPHIA, PENNSYLVANIA.

PACKING.

SPECIFICATION forming part of Letters Patent No. 751,884, dated February 9, 1904.

Application filed July 27, 1903. Serial No. 167,222. (No model.)

To all whom it may concern:

Be it known that I, WILLIAM J. M. WEAVER, a citizen of the United States, residing in Philadelphia, Pennsylvania, have invented 5 certain Improvements in Packing, of which the following is a specification.

My invention consists of certain improvements in self-lubricating packing particularly designed for use in stuffing-boxes to prevent 10 leakage of steam, water, or other fluid around a rod or plunger passing through said box, the object of the invention being to provide a packing of such construction that the lubricant contained in it shall be delivered under 15 operating conditions to the surface of the rod or plunger, so as to prevent undue friction between it and the packing.

A further object of the invention is to provide means for the retention of the lubricant, so 20 that this shall be delivered from time to time to the moving surface of the rod or plunger in a manner such as to most efficiently perform its function.

These objects I attain as hereinafter set 25 forth, reference being had to the accompanying drawings, in which—

Figure 1 is a perspective view of a section of packing constructed in accordance with my invention, showing the preferred arrangement 30 of the container or reservoir for lubricant. Fig. 2 is a vertical sectional view of a piece of packing constructed the same as that shown in Fig. 1, but without the perforations in the containing-section for the lubricant. Fig. 3 is a sectional elevation of another form 35 of my improved packing in which the containing-section for lubricant has the form of a section of a cylinder. Fig. 4 is a sectional elevation of a piece of packing, showing the 40 containing-piece for the lubricant extended between the wedges as well as between the cushion and the wedges. Fig. 5 is a sectional elevation of a special form of my improved packing, showing the lubricant-container of a 45 curved or bent section and extending into the body of the cushion. Fig. 6 is a form of my improved packing in which the container for the lubricant is in the form of a tube extending longitudinally of the packing and provided with perforations, said tube being 50

placed between the cushion and the wedges; and Fig. 7 is a sectional elevation of a form of my improved packing in which the container for lubricant is given the form of a corrugated strip extending through the packing, 55 the lubricant being contained between the corrugations of said strip.

In the above drawings the figures represent the various forms of packing, in each case including two wedge-sections A and A' 60 and a cushion-section B, these being elements well known to the art and common to many forms of packing. The wedges are usually formed of a number of parallel layers of fabric and have between them some device or 65 compound to promote their sliding upon one another and which prevents their sticking together, such as graphite or a sheet of material b², of metal or other hard substance.

The cushion-section B usually consists of 70 hemp or cotton either twisted into a number of strands, as shown at b in Fig. 1, or laid in any other desired manner. Between the cushion-section and the wedge-section I place some form of container or reservoir in which is 75 held a body of lubricant—such, for example, as tallow and grease or graphite.

In Fig. 1 my container consists of a Z-shaped piece of soft metal C, extending longitudinally through the packing and lying between the 80 top surface of one of the wedges and the cushion B. In the wedge-shaped space formed by the folds of this piece C the graphite and grease or other lubricant is placed, and I preferably perforate the central fold of the piece C, so 85 that said lubricant may easily pass from one to the other of the wedge-shaped spaces.

As customary in the type of packing illustrated, the wedges, cushion, and lubricant-container are all held in place by a covering 90 or jacket of fabric, as shown at D.

As illustrated in Figs. 3 and 6, the lubricant may be contained in a tube of such material as lead or soft metal having perforations in its sides, and, as before, placed between the 95 cushion and the wedges.

In the forms shown in Figs. 4 and 5 the lubricant is contained between two substantially parallel sheets of metal, rubber, &c., so placed between the wedges and cushions as to be free 100

to be pressed out at the sides of the packing when pressure is applied to the same under working conditions.

In the case of the packing illustrated in Fig. 5 the sheets between which the lubricant is held are bent or curved upwardly, so as to retain in a given width a greater body of lubricant than if the sheets extended across the top of the wedge without such curving.

In Fig. 4 in addition to extending across between the top of one of the wedges and the cushions the reservoir for the lubricant is extended down between the wedges, being open at both ends, so that under pressure the lubricant is caused to exude at two points on one side of the packing.

In Fig. 7 a single sheet of metal, rubber, &c., is corrugated and provided with lubricant, which is held between its corrugations, said lubricant, as before, feeding out on either side of the packing when pressure is applied.

In any case it will be noted that the sheet forming the sides of the container for lubricant are of a width relatively greater than the width of the packing in which they are employed.

I claim as my invention—

1. In a packing, the combination of a plurality of bodies of material extending longitudinally of the same, certain of said bodies being composed of sheets of fabric and another body consisting of a relatively loose fibrous material, with a containing device extending between the said bodies of material, and lubricant in said containing device, substantially as described.

2. The combination of a packing including wedges and a cushion, with a container for lubricant extending longitudinally of the packing between the cushion and said wedges, and a body of lubricating material held by said container, substantially as described.

3. The combination in a packing, of wedges and a cushion, with a containing device extending longitudinally of the packing and placed between the cushion and the top surface of one of the wedges, and a body of lubricating material held by the containing device, said device having an opening for permitting said lubricating material to pass out at the side of the packing substantially as described.

4. The combination in a packing, of a cushion, and a pair of wedges, with a containing device extending between the cushion and the wedges and between the wedges, and a body of lubricating material held by said containing device, substantially as described.

5. The combination in a packing, including a cushion and two substantially wedge-shaped sections, of a receptacle consisting of substantially parallel sheets of material having be-

tween them a body of lubricant and placed between the cushions and the wedge-shaped sections, substantially as described.

6. The combination in a packing, of a cushion, with a body of relatively solid material containing fabric, extending parallel to the body of the cushion, a receptacle consisting of substantially parallel sheets of material placed between the cushion and said body of fabric-containing material, and a lubricant between said sheets of material, said receptacle being constructed so that the said lubricant is free to pass out of it at the side of the packing, substantially as specified.

7. The combination in a packing, of a cushion, and two substantially wedge-shaped sections, with a plurality of sheets of material extending substantially parallel to each other between the wedge-shaped sections, and between one of the sections and the cushion, with a body of lubricating material contained between said sheets, substantially as described.

8. The combination in a packing, of a cushion-section, and a pair of wedge-shaped sections, with a body of lubricant between said wedge-sections and the cushion, and a container for said lubricant, said container having openings in its sides, substantially as described.

9. The combination in a packing, of a cushion, a relatively solid body of material containing fabric, and a plurality of sheets of material between said body and the cushion, said sheets being some distance apart and containing between them a body of lubricating material, the sheets being of a width greater than the width of the packing, substantially as described.

10. The combination in a packing, of a cushion, and a pair of wedge-shaped sections, with a sheet of lead between the cushion and the wedge-sections, said sheet being bent to form a receptacle and a body of lubricating material contained in said receptacle, substantially as specified.

11. The combination of a cushion-section with two wedge-sections and a piece of material between said cushion-section and the wedge-sections, said piece of material being folded upon itself in such manner as to form a receptacle, and a body of lubricating material held in said receptacle, substantially as described.

In testimony whereof I have signed my name to this specification in the presence of two subscribing witnesses.

WILLIAM J. M. WEAVER.
